UNITED STATES PATENT OFFICE

2,473,674

NOZZLE

Frederick Boehm, Philadelphia, Pa., assignor to
Schutte and Koerting Company, Philadelphia,
Pa., a corporation of Pennsylvania

Application November 25, 1944, Serial No. 565,078.

4 Claims. (Cl. 299—117)

1

This invention relates to nozzles and has particular reference to the type of nozzle producing a conical spray of liquid.

The conical sprays produced by nozzles generally have their cone angles defined by spiral guide members, slotted plugs or tangential channels inside the nozzles. These guide members have heretofore generally been cast and since they must be smoothly finished to prevent energy losses in the nozzles, a process which must be accomplished by hand or machine work, they have been a relatively expensive part of the nozzle. Furthermore, if a particular nozzle is to be capable of providing sprays of different angles, it is necessary to replace the guide members since each is capable of defining only one cone angle.

In accordance with the present invention a spiral guide is provided which is of simple construction even in its preferred adjustable form. Briefly, the guide is made up of stacked discs provided with radially extending spokes, which discs, when assembled with these spokes displaced progressively about the axis, will define spiral passages for the guidance of the liquid as it approaches the outlet of the nozzle. In one form of the invention provision is made for changing the angular relationships of the discs thereby to provide spiral passages of adjustable pitch. The invention, however, is also adapted to the production of a spiral guide of fixed pitch, this having the advantage of simplicity of construction and involving the possibility of making guides of different fixed pitches using for all of them identical stampings and merely providing, to define the different pitches, central members having no more than spiral grooves of different pitches provided therein.

The objects of the invention relate primarily to the general features mentioned above. Other objects of the invention particularly relating to details of construction will be apparent from the following description read in conjunction with the accompanying drawings in which:

Figure 1 is an axial section through a preferred embodiment of the invention in the form of a nozzle having a variable pitch guideway for the liquid;

Figure 2 is a transverse section taken on the plane, the trace of which is indicated at 2—2 in Figure 1;

Figure 3 is a transverse section similar to Figure 2 but showing the spiral having a relatively small pitch as compared with Figure 2 in which the pitch is infinite;

Figure 4 is an elevation of the upper portion

2

of the nozzle showing index markings whereby a user may determine the angle of spray or stream which will be produced;

Figure 5 is a diagrammatic perspective view illustrating the fashion in which the pitches of the various stampings are controlled;

Figure 6 is an axial section through a nozzle provided in accordance with the invention, but having a guide of fixed pitch;

Figure 7 is a perspective view showing the stampings used in the arrangement of Figure 6;

Figure 8 is an axial section through still another form of nozzle having an adjustable guideway but in which the control of the adjustment takes a different form; and

Figure 9 is a section taken through the nozzle of Figure 8 and showing in particular the means controlling the pitch.

Referring first to the modification shown in Figures 1 to 5, the body of the nozzle is indicated at 2, threaded at 4 for attachment to a pipe. A cap member 6 threaded externally to the body is arranged to clamp in position the conical part 8 of the nozzle.

Elements 10 in the form of stampings are adapted to be stacked in the nozzle as indicated in Figure 1. Each of these comprises a circular periphery 12 joined by arms or spokes 14 to a hub portion 16 provided with a central opening.

These stampings are desirably of quite thin sheet metal, the thickness of which is substantially exaggerated in Figure 1. The stack of stampings is supported on the inwardly directed flange 18 within the body 2 and is clamped between this flange and the inwardly directed flange 20 at the base of the conical portion of the nozzle. Passing through the central openings of the stampings is the shank 22 of the conical guide 24, a washer 26 and cotter pin 28 holding the stampings on the shank 22 beneath the base of the cone 24. In the flanges 18 and 20 are holes 30 and 32 of corresponding angular spacings, for example 90°, for the reception of wires or tightly wound small spiral springs 34 which are threaded through

45 corresponding holes in the stampings. On the conical portion 8 of the nozzle there are provided index markings such as 36 which may be brought into alignment with a fixed index marking (not shown) on the body 2 of the nozzle.

45 If the openings 32 in the flange 20 are aligned axially with the openings 30 in the flange 18, in which case the zero marking of the index 36 is aligned with the zero index on the nozzle body 2, the wires or equivalent elements 34 will be parallel to the nozzle axis and the stampings will

55

If the openings 32 in the flange 20 are aligned axially with the openings 30 in the flange 18, in which case the zero marking of the index 36 is aligned with the zero index on the nozzle body 2, the wires or equivalent elements 34 will be parallel to the nozzle axis and the stampings will

be so aligned that their spokes or arms 14 will form radially extending walls thereby defining passages of infinite pitch. Under such conditions no rotation will be imparted to the liquid flowing through the nozzle and there will emerge from the nozzle a solid stream of the liquid having a zero cone angle. When such adjustment is effected it is, of course, maintained merely by tightening down the collar 6.

If, however, the conical part 8 of the nozzle is rotated with respect to the body 2 the openings 32 and 30 will be angularly misaligned with the result that the guide elements 34 will be constrained to take spiral positions, the pitch of which will depend upon the degree of angular displacement of the elements 8 and 2. Inasmuch as the wires or spiral springs or the like preclude the presence of sharp angles along their lengths, the stampings will be displaced at progressive small angles relative to each other thereby providing spiral passages defined by the edges of the radial arms 14 such as indicated at 38 in Figure 3. It will be evident that the passage walls will actually be in the form of steps. If the stampings, however, are very thin these steps will be correspondingly small and reasonably smooth guide passages will be provided quite comparable with those heretofore existing in the case of the cast spiral guides followed by ordinary smoothing by hand filing.

It will be evident that a large variety of pitches may be achieved by adjustment in the fashion described, any particular adjustment being maintained by the clamp action of the collar 6 which is freed for the purpose of making an adjustment. The index markings 36 may be calibrated in terms of the cone angles of the spray produced in the various adjustments. While in the particular type of nozzle illustrated the cone will be of the so-called hollow type it will be evident that the invention is applicable to any type of spray nozzle where adjustment of the spray may be effected by the presence of guides of different pitches.

The type of spiral guide which has been described may obviously be of fixed pitch and this possibility leads to a simple nozzle construction such as illustrated in Figures 6 and 7. In this modification a body 2 is assembled with the conical part 42 of the nozzle and clamped between them is a stack of discs 48 of the same general type as heretofore described, being in the form of thin stampings provided with radial arms connecting peripheral and central portions. These discs are assembled upon the shank of the cone 44 between the base of the cone and a washer 52 held in position by a cotter pin 54. A spiral groove 46 formed in the shank serves to receive small projections 50 extending inwardly into the central openings of the stampings. When the stampings are located on the shank, therefore, they will have progressive angular relationships to define a spiral guide passage having a pitch corresponding to that of the groove 46. It will be evident that the angular location of these stampings may be defined by interconnection of any elements on the stampings with a spiral member which specifically is shown as a groove 46.

The advantage of an arrangement such as that of Figures 6 and 7 lies in the fact that stampings of the type indicated in Figure 7 may be identical for nozzles having fixed spirals of a greater variety of pitches, since the pitch of the final spiral passages is determined simply by the pitch of a groove such as 46.

Whether a fixed or adjustable spiral is pro-

vided it will be evident that the invention may take numerous forms. Figures 8 and 9 illustrate a further modification of the invention in which an adjustable spiral is provided. In this case the conical nozzle part 56 and body 58 are assembled as in Figure 1 through the medium of a collar or cap 60. A disc 62 is located below the conical part 56, for example by pins to prevent angular displacement relative thereto. This disc 62 may carry the central conical guide 64. Similarly, another element 66 is pinned or likewise secured to the part 58. There are provided non-circular openings in the elements 62 and 66, and extending through these openings is an elastic or deformable element such as may be constituted by a rubber non-circular strip or preferably by a bundle of wires such as 68 having a non-circular enveloping cross-section. Stampings 70 of the same general type as those illustrated in the first modification are provided with a corresponding non-circular opening such as 69 so as to receive the assembly of the elements such as 68. It will be evident that in this modification as in the one first described relative rotation of the cone element 56 and the body 58 will provide a progressive spiral in the central guide member providing a corresponding spiral arrangement of the radial arms of the stampings and thus defining spiral guide passages for the liquid.

It will be clear that the invention may take numerous other forms without departing from the scope thereof as defined in the following claims.

What I claim and desire to protect by Letters Patent is:

1. A nozzle comprising a body having a pair of relatively angularly displaceable members and having a passage for fluid therethrough, means defining helical portions of said passage comprising a series of thin elements having outwardly extending arms, the arms of the elements being progressively angularly displaceable to provide helical bounding walls for said portions of the passage, means interconnecting said members and said thin elements and adapted to assume helical shapes of pitches dependent upon the relative angular displacements of said members, thereby to control the pitch of said helical portions of said passages, said interconnecting means comprising flexible members passing through openings in the peripheral portions of said thin elements, and means to secure said elements between said body members.

2. A nozzle comprising a body having a passage for fluid therethrough, a series of thin elements each comprising an outer and inner annulus connected by arms and capable of being progressively angularly displaced whereby said arms form helical bounding walls for portions of said passage, flexible means passing through openings in the outer annuli of said elements for controlling the progressive angular displacements of said elements and means to secure said elements in the body.

3. A nozzle comprising a body having a pair of relatively angularly displaceable members and having a passage for fluid therethrough, a series of thin elements each comprising an inner and outer annulus connected by arms, said elements being progressively angularly displaceable whereby said arms form helical bounding walls for portions of said passage for fluid, flexible means interconnecting said members and the outer annuli of said thin elements and adapted to assume helical shapes of pitches dependent upon the relative

angular displacements of said members thereby to control the pitch of said helical portions of said passages and means to secure said body members and elements in adjusted positions.

4. A nozzle comprising a body having a pair of relatively angularly displaceable members and having a passage for fluid therethrough, a series of thin elements each comprising an inner and an outer annulus connected by arms, said thin elements being progressively angularly displaceable whereby said arms form helical bounding walls for portions of said passage, means interconnecting said members and said thin elements and adapted to assume helical shapes of pitches dependent upon the relative angular displacements of said members thereby to control the pitch of said helical portions of said passages, said interconnecting means comprising a plu-

rality of flexible members passing through openings in the outer annuli of said elements and into said body members and means to secure said elements between said body members.

FREDERICK BOEHM.
